SANITARY COMMUNION SERVICE.

No. 553,846.

Patented Feb. 4, 1896.

UNITED STATES PATENT OFFICE.

CHARLES FORBES, OF ROCHESTER, NEW YORK.

SANITARY COMMUNION-SERVICE.

SPECIFICATION forming part of Letters Patent No. 553,846, dated February 4, 1896.

Application filed July 13, 1894. Serial No. 517,477. (No model.)

To all whom it may concern:

Be it known that I, CHARLES FORBES, a citizen of the United States of America, and a resident of Rochester, in the State of New York, 5 have invented a new and useful Improvement in Sanitary Communion-Service, of which the following is a specification.

This invention relates to the apparatus or "service" employed in churches for administering the sacrament of the "Lord's Supper," or, as it is commonly termed, the "Holy Communion," and to that new variety of such communion-service in which each communicant is furnished with an individual cup to avoid 15 the sanitary objections to passing a cup or chalice from mouth to mouth.

The present invention consists in sanitary cup-racks for individual communion-cups, and in novel combinations of parts embodied 20 therein, together with a sanitary bread-tray, incorporated with a specific form of such racks as part thereof, as hereinafter set forth and claimed.

Several of the said novel combinations of 25 parts comprise cup-holders so constructed as to hold the individual cups in ranks, which, together with a central horizontal handle at top, are parallel with the sides of a narrow rack, so as to facilitate passing the rack from 30 hand to hand in the pews of a church; also in ranks of uniform length exposed at the sides of the rack, so as to provide for filling the cups by ranks with rapidity and with reduced exposure to the atmosphere as compared with other arrangements.

Another feature on which certain claims are based is the adaptation of the cup-holders to so coact with handle extensions on a peculiar style of cup as to keep the handles outermost, to limit the descent of the cups within 40 bottomless cup-receiving holes, and to assist in steadyng the cups within the rack.

Another feature preferably common to each of the cup-holders hereinafter described and 45 to each bread-tray combined therewith is dust-excluding covers, each cup-cover serving conveniently for a rank of cups at least, while those of the entire rack may be manipulated simultaneously, so as to provide for 50 readily filling the cups *in situ* as well as to provide for readily inserting and withdrawing the cups individually. Such dust-exclud-

ing covers serve to prevent foreign matter and germs of such diseases as diphtheria, scarlet fever, measles and other eruptive diseases from falling into the cups or upon the bread from the clothing of the communicants. They also admit of the cups being filled the day before communion, as they serve to prevent any evaporation of the wine after they 60 are lowered, and to exclude insects and motes of every description.

Four sheets of drawings accompany this specification as part thereof.

Figure I of the drawings is a perspective view of a combined cup-rack and bread-tray with its cup-covers elevated and two ranks of cups removed. Fig. II is a perspective view of one of the cups, on a larger scale. Fig. III is a vertical cross-section through said combined 65 cup-rack and bread-tray, Fig. I, on the same scale as Fig. II. Fig. IV is a fragmentary horizontal section on the line *a b*, Fig. III. Fig. V is a half vertical cross-section of a sanitary cup-rack, illustrating certain modifications. Fig. VI is a fragmentary elevation projected from Fig. V. Fig. VII is a fragmentary horizontal section on the line *c d*, Fig. V. Fig. VIII is a fragmentary end elevation illustrating additional modifications. Fig. IX is a sectional plan view projected from Fig. VIII. Fig. X is a fragmentary end view illustrating another modification. Fig. XI is a fragmentary vertical cross-section illustrating additional modifications. Figs. XII and XIII are 80 respectively top and end views, both of them fragmentary, illustrating additional modifications. Fig. XIV is a fragmentary sectional elevation illustrating additional modifications. Fig. XV is an end elevation of another 90 modified cup-rack. Fig. XVI is a fragmentary vertical section at *e f*, Fig. XV. Fig. XVII is a handle detail projected from Fig. XV. Fig. XVIII is a vertical cross-section of a pew-rack for empty cups, and Fig. XIX is 95 a sectional elevation of a suitable cup-filling device.

Like letters and numbers refer to like parts in all the figures.

The term "cup-rack," as hereinbefore and 100 hereinafter employed, is intended to include the upright form represented at A in Figs. I, III, V, VIII, and XI, and also flatter or tray-like forms, such as the one represented at A²

in Fig. XV; the term "bread-tray" to include not only the specific rectangular form represented at B in Figs. I and III, but also any other approved form capable of being combined with a cup-rack, and the term "cup" to include cups having handles, as shown at C in Figs. I, II, and III, and at C² in Fig. V, of metal or of glass or the like, and also handleless glasses, as represented at C³ in Figs. VIII, IX, X, XII, XIII, XIV, XV, XVIII, and XIX, or similar cups of metal or the like, and goblet-shaped chalices, as represented at C⁴ in Fig. XI, or any other approved form of individual communion-cup.

15 In the specific combination represented by Figs. I to IV, inclusive, the cup-rack A comprises a rectangular bottom frame 1, a pair of end uprights 2, and cup-holders 3 in the form of successive terraces one above another, all 20 of which are conveniently made of suitable wood and rigidly united with each other; and each of said cup-holders has vertical holes 4 fitted to the bottoms of its complement of the cups C, and gage-surfaces 5 at its outer edges 25 which coact with downward extensions 6 of the cup-handles to keep the handles uniformly outermost when the cups are in the rack, as in Figs. I and III, and to aid in supporting the cups against tilting, and also to limit the 30 descent of the cups within such holes. (See Fig. III.) The cups are thus held in ranks of uniform length, preferably of ten each, parallel with each other at the respective sides of the rack and one above another, so that the base 35 of the rack may be as narrow as practicable, in order to economize room on the communion-table and to facilitate passing the rack in the pews.

40 A flat dust-excluding cup-cover 7, of metal or other suitable material, extends over each rank of cups. A pair of U-shaped slides 9 are guided by vertical grooves 10 in the inner faces of the end uprights 2, and are provided with notches 11, Fig. IV, fitted to the 45 runners 8 at the respective ends of the cup-rack, and detent-springs 12, of wire, attached at their ends to said uprights 2, engage with central notches 13 in the runners 8 to keep the covers normally above both ranks of the cups 50 beneath, as in full lines in Fig. III. By lifting on the two slides 9 the cup-covers may be raised simultaneously to the elevated positions in which they are shown in Fig. I and in full lines in Fig. III, and when they are 55 thus lifted each pair of covers may be slid horizontally, as represented by dotted lines at 7^x in Fig. III, to expose the ranks of cups individually to a greater extent when the cups are to be filled. When the cup-covers are 60 lowered upon the cups, as at 7^y in Fig. III, downwardly-projecting flanges 14 coact with those ranks of cups which are most widely separated, as at 14^y in Fig. III, to keep the cups from tilting inward, and all the cup-covers 65 perform their other and principal functions hereinbefore set forth.

Immediately above the topmost of the cup-

covers 7 a bread-tray B is suitably supported between the upper ends of the end uprights 2, being constructed with dust-excluding covers 15, which remain open, as at 15^y in Fig. III, only long enough to introduce the portions of bread, corresponding in number with the cups at the respective sides of the cup-rack, and while they are being taken therefrom by the individual communicants. These covers are conveniently hinged, as at 16 in Fig. III, and the tray is conveniently divided by a central longitudinal partition 17, Fig. III, into two compartments, one beneath each 80 of the covers 15.

A central horizontal handle 18, parallel with the sides of the rack, is rigidly connected with the upper ends of the end uprights 2 by stay-wires 19, so as to rigidly unite said end uprights and to serve in common for the cup-rack and bread-tray, which are thus combined in one convenient article of symmetrical proportions.

25 In the modified arrangement represented by Figs. V to VII, inclusive, the cup-rack A comprises a wooden bottom 1 and end uprights 2, substantially similar to those of the form above described, cup-covers 7 and cover-runners 8, identical with those above described, and also the above-described central horizontal handle 18 and handle-stays 19. Instead of the wooden cup-supports above described, metallic cup-supports 3 coact with downwardly-projecting handle extensions 6, 100 as in the combination above described, and with those portions of the respective cups underlying said handle extensions, and are furthermore constructed with vertical notches 20, Fig. VI, to coact with wrists 21 (see Fig. 105 II) connecting the lower end of each handle with the body of the cup immediately above the handle extension 6, so that the cup may be wholly supported from this one point, and the vertical slides 9, instead of being made of 110 round wire, as in Figs. I, III and IV, are made of flat metal, (see Fig. VII,) so as to readily accommodate larger notches 11 for the cover-runners 8. Suitable grooves 10 for these slides are readily formed by saw-kerfs in the 115 end uprights 2, and wire springs 22 within said grooves, coacting with the inner edges of said slides within said grooves, serve at once to hold the slides and the runners by friction against accidental displacement. 120

125 A supplemental cover 23 is provided with hinges 24, and supported by a middle portion 25 between the upper ends of the end uprights 2, which are provided with stops 26 to support the respective leaves of the cover in 125 horizontal position. They are turned up temporarily while the cups are being filled and serve at other times to aid in preventing any accumulation of dust on the cups beneath when the cup-rack is not provided with a 130 bread-tray at top.

135 In the modified cup-rack represented by Figs. VIII and IX, handleless cups or glasses C³, as shown, or said cups C or C² or C⁴, if

preferred, are held between pairs of fingers 3, which partly embrace the cup and are preferably elastic, so that the cup may be withdrawn laterally from between them without damage if not first lifted so as to free it, such fingers being conveniently supported by horizontal bars 27, as in Fig. IX, between the end uprights 2 of the rack. Said end uprights are provided with slots 28, having metal linings 29, to admit the shanks of a pair of thumb-lugs 30, by which a pair of vertical slides 31 are operated, and the cup-covers 7 are hinged to horizontal bars 32 carried by said vertical slides. By screwing the shanks of said thumb-lugs into said slides 31, as represented in Fig. IX, provision is readily made for fastening the covers in their elevated positions, (represented by dotted lines in Fig. VIII,) by a slight turn of the thumb-lugs. By hinging the covers they are adapted to be turned up and lowered individually, as represented by the dotted arcs at 7^a in Fig. VIII, for the filling operation. They are simultaneously elevated by lifting on the loosened thumb-lugs 30 to facilitate the withdrawal of the cups by the communicants.

18, Fig. VIII, may represent a horizontal handle at top, of the same length as the rack, or longer, if desired, and 19 either curved or 30 vertical rods connecting the handle with the respective end uprights 2.

In Fig. X, 2 represents the rod-shaped end uprights of another modified rack; 3 3, cup-holders similar to those last described, Figs. VIII and IX; 77, cup-covers; 19, the handle-rods of the rack; 27, a horizontal bar supporting said cup-holders, and 33 hinges attaching said covers to said horizontal bar, so that the hinges are located close to the cups 40 C³ as they hang in their holders 3, and provide for freeing the cups from their holders by tilting, as in dotted lines in Fig. X, and for withdrawing them from beneath the covers without first elevating the latter relatively 45 to the cups.

The modified rack represented by Fig. XI comprises end uprights 2, and cup-holders 3 in the form of horizontal shelves provided with slotted or split stud-pins 34, to which 50 sockets in the bottoms and stems of goblet-shaped chalices C⁴ are fitted. The slots adapt the pins to act as retaining-springs. It further comprises cup-covers 7, each common to two ranks of cups, and a simple device whereby 55 the covers are simultaneously elevated and swung to either side, as in dotted lines in the figure, to facilitate filling the cups and their withdrawal from the rack by the communicants. To render the covers 7 thus movable, 60 they are rigidly attached to vertical end bars 35. These are connected by pivots 36 to short parallel links 37, two or more to each bar, and said links 37 are pivoted to the end uprights 2 by countersunk screws 38, for 65 which other suitable pivots may of course be substituted. All the covers are moved simultaneously to either side by lifting either cover

and gently drawing or pressing it away from the side of the rack which is to be opened.

In Figs. XII and XIII, 3 represents a cup-holder in the form of a shelf having segmental notches 39, open at its outer edge, and of a diameter intermediate between the lesser and greater diameters of the cups C³, (or C' or C²), so that the cups are suspended in their 70 holders, as in the modifications represented by Figs. VIII, IX and X, while at the same time the holders are rigid, and the cups are freed from them by lifting them slightly and then drawing them outward, as represented 75 by dotted lines at C³ in Fig. XIII; and 7 represents a dust-excluding cup-cover projecting rigidly at a sufficient height above a rank of cups to provide for readily withdrawing the cups from beneath it. 40 40, Fig. XII, 80 represent nails or pins to keep wooden cup-supporting shelves so notched from warping or splitting.

In Fig. XIV, 3 represents a cup-holder in the form of a stamped sheet-metal shelf having a cup-shaped socket for each cup; 7 represents a flexible cup-cover; 41 represents a roller upon which the cover may be wound to expose the cups when they are to be filled or distributed, and 42 represents a stiffening 95 and weighting wire at the outer edge of the cover. A cover of this description may answer for two or more ranks of cups, if desired.

The tray-shaped cup-rack A² (represented by Figs. XV, XVI, and XVII) comprises cup-holders 3 in the form of double terraces, provided with vertical holes 4, as in the arrangement first described, but preferably of sufficient size to allow handleless cups C³ to set more deeply in them, as in Fig. XV, so as to 100 be steadily supported, and with the edges of successive terraces retreating inward the width of the two ranks of cups supported by the terraces beneath, and with the tops of the successive terraces on a level with the tops 105 of the cups supported by the terraces next below. When the cup-holders 3 are of wood, their holes 4 are preferably lined with metal, as at 43 in Fig. XVI, to preserve the diameter of hole. Cup-covers 7 for all except the 110 uppermost cups are conveniently hinged to the outer edges of the cup-holders 3. Those of the uppermost cups are hinged in like manner to a middle bar 44. The hinges of all the covers in this arrangement are preferably so 115 formed that the covers can be turned up, as in dotted lines at 7^a in Fig. XV, to facilitate filling the cups by ranks, or, as at 7^b, while the cups beneath are being removed, as in dotted lines at C³, and can be dropped down 120 out of the way, as at 7^c, when all the cups beneath have been removed. A suitable base 125 45 and spacing-blocks 46 between the lowermost and middle cup-holders, a central longitudinal frame-piece 47, a horizontal longitudinal handle 18 at top, and a pair of curved handle-bars 19, pinned fast at their outer ends within said frame-piece 47, complete the 130 cup-rack. The longitudinal bar 44 which sup-

ports the uppermost cup-covers is conveniently fastened to vertical portions of said handle-bars 19, with the aid of collars 48 on the latter.

5 To receive the emptied handleless cups C³, especially when these are of thin glass, as represented in the drawings, an empty-cup rack E, Fig. XVIII, may be temporarily suspended in each pew, the same to be composed 10 of a bottom 49, a back 50, and a top 51, united with each other, said top having a sufficient number of holes 52 fitted to the cups at their upper edges and being so located above the bottom 49 as to inclose and protect the thin 15 lips of the cups. Hanging bars having key-hole-slots are represented at 53, and wood-screws to coat therewith are represented at 54. Other forms of the individual cups may be cared for after they have been emptied in 20 any approved way.

For filling the cups after they have been arranged in the cup-racks A or A², so as to fill all the cups in one rank at one operation and with uniformity and neatness, a filling 25 device, Fig. XIX, adapted to be so used, preferably forms part of the sanitary communion-service, and is conveniently constructed as follows: A bottle F of suitable 30 capacity is constructed with a vertical neck 55 at its upper end and with a horizontal neck 56 at or near its bottom. A horizontal distributing-tube D is tightly fitted to said horizontal neck by means of a bushing 57 within the latter, and is provided at bottom with a 35 series of outlets 58 corresponding in number with a rank of cups and as to distance apart with the centers of the cups, and a stopper 59 closes the outer end of the tube. In filling the bottle F it is tilted about forty-five 40 degrees, when the first outlet in the distributing-tube D will be sufficiently high to prevent any escape therethrough while the wine is being poured in. A hollow stopper 60 and an air-tube 61 extending therethrough are 45 now inserted into and through the vertical neck 55, as in Fig. XIX. The bottle F is grasped in one hand and the outer end of the distributing-tube D with the other, and after the outlets 58 are located above a rank 50 of cups, as in Fig. XIX, the finger is removed from the upper end of the equalizing-tube 61 and the wine flows simultaneously into all the cups. The flow is stopped by replacing the finger on the upper end of the tube 61. The 55 distributing-tube D is then located above another rank of cups. These are filled in like manner, and thus the filling operation proceeds until all the cups of the rack have been filled, after which its cup-covers are 60 lowered and it is placed on the communion table or altar until it is required in the distribution of the elements. The cup-covers are then elevated, as in Fig. I, and each communicant is permitted to take a cup from the 65 cup-rack, together with a piece of bread from the bread-tray, if the two are combined, as in Figs. I and III; and the distribution pro-

ceeds in this manner until all have partaken, the empty cups being cared for as above.

In the combined cup-rack and bread-tray 70 the bread-tray B may be attached to the cover-lifting slides 9, and may be adapted to slide laterally, like the cup-covers 7, to facilitate at once access to the cups beneath in the filling operation and the removal of the bread-tray for cleansing. The cup-holders may extend beyond the end uprights at the ends of the rack, with the end cups in transverse ranks and with covers correspondingly constructed. The cups C⁴, when held between 75 spring-fingers 3, Figs. VIII and IX, as above described, may be grasped thereby near the top, like the cups C³, or preferably at the base, and other like modifications will suggest themselves to those skilled in the art. 80

The aforesaid filling device, Fig. XIX, forms no part of my present invention, but is shown and described to illustrate a distinctive function of the sanitary cup-racks as provided with cup-holders for individual cups in 90 ranks of uniform length, and with cup-covers adapted to expose the cups so that they may be filled *in situ* and a rank at each filling operation, as above described.

Having thus described the said improvement, I claim as my invention and desire to 95 patent under this specification—

1. In a sanitary communion-service, a portable cup-rack, for individual cups, having cup-holders which locate the cups in ranks 100 of uniform length parallel to the sides of the rack, and dust-excluding cup-covers, forming part of the rack, which are movable to expose the ranks of cups within the rack, whereby all the cups of each rank may be 105 filled at one operation by a suitable filling device, substantially as hereinbefore specified.

2. In a sanitary communion-service, a portable cup-rack, for individual communion-cups, having a vertical series of cup-holders which locate the cups in ranks one above another parallel to the sides of the rack, a like series of dust-excluding cup-covers each of 110 which is common to a rank of cups and is movable relatively to the cup-holder beneath to expose the cups, and a central horizontal handle at top parallel to the sides of the rack, substantially as hereinbefore specified. 115

3. A sanitary cup-rack having cup-holders 120 for individual communion-cups in parallel ranks one above another, dust-excluding cup-covers each of which is common to a rank of cups and is movable vertically relatively to the cup-holder beneath, and means for raising and lowering all the cup-covers simultaneously, substantially as hereinbefore specified. 125

4. A sanitary cup-rack having cup-holders 130 for individual communion-cups in parallel ranks, and dust-excluding cup-covers each of which is common to a rank of cups and is movable vertically and laterally to expose the cups beneath for the filling operation.

5. The combination, in a sanitary cup-rack, of dust-excluding cup-covers provided at their ends with horizontal runners, vertical slides notched to form guides for said runners, and 5 vertically-grooved end uprights forming guides for said slides, substantially as hereinbefore specified.

6. The combination, in a sanitary cup-rack, of dust-excluding cup-covers provided at their 10 ends with notched horizontal runners, vertical slides notched to form guides for said runners, vertically-grooved end uprights forming guides for said slides, and detent-springs 15 acting with said runners to fasten the cup-covers in their central positions, substantially as hereinbefore specified.

7. A sanitary cup-rack having cup-holders constructed with bottomless cup-receiving holes and with gage-surfaces at the outer 20 edges of the cup-holders, in combination with individual communion-cups having handles and constructed with downwardly-projecting handle-extensions which coact with said gage-surfaces to keep the handles outermost and 25 to assist in supporting the cups, substantially as hereinbefore specified.

8. A sanitary cup-rack for individual communion-cups having cup-holders arranged in successive terraces for ranks of cups at different levels, dust-excluding cup-covers at the 30

respective levels, a covered bread-tray supported above the topmost cup-covers, and end uprights common to all, substantially as hereinbefore specified.

9. A sanitary cup-rack for individual communion-cups having cup-holders arranged in successive terraces for ranks of cups at different levels, dust-excluding cup-covers at the 35 respective levels, cover-elevating devices common to all said cup-covers, a covered bread-tray above the topmost cup-covers, and end uprights common to all, substantially as hereinbefore specified.

10. A combined cup-rack and bread-tray composed of a bottom frame, a pair of end uprights, a horizontal handle at top, cup-holders for individual cups in ranks one above another at both sides of the rack, and a bread-tray immediately beneath the handle, all of which may be fixedly united with each other, 45 movable dust-excluding cup-covers above the respective cup-holders, cover-lifting devices at the ends of the cup-covers, and movable covers for the bread-tray, substantially as hereinbefore specified. 50
